UNITED STATES PATENT OFFICE.

WILLIAM M. KECK, OF COALINGA, CALIFORNIA.

UNDERREAMER.

1,202,727.

Specification of Letters Patent.

Patented Oct. 24, 1916.

Application filed December 2, 1915. Serial No. 64,739.

To all whom it may concern:

Be it known that I, WILLIAM M. KECK, a citizen of the United States, residing at Coalinga, in the county of Fresno and State 5 of California, have invented certain new and useful Improvements in Underreamers, of which the following is a specification.

The present invention relates to an underreamer for drilling and reaming wells below 10 the bottom of the well-casing, so that said casing may be easily sunk.

Inasmuch as underreamers of this type must be lowered and raised through the well-casing, means must be provided for expanding the cutters when the same are projected below the bottom of the casing, in order to 15 ream out the well to a diameter equal to that of the outside of said casing, and to retract or withdraw the cutters within the body of 20 the reamer to allow the same to pass through the casing. This must be done automatically, because the entire reamer is suspended in the well by means of a rod or cable. Moreover, 25 the cutters must be positively locked when in their operative position, and securely supported by the body of the reamer, in order to withstand the strains imposed upon them.

To this end the invention has for its object 30 the provision of an underreamer of simple and sturdy construction, the cutters of which are automatically expanded when the device is dropped below the bottom of the well casing, and retracted when drawn up into said casing, and in addition, said cutters 35 are firmly held and locked when in operative position.

In order to comprehend the invention, reference should be had to the accompanying sheets of drawings, in which—

- 40 Figure 1 is a sectional elevation of the underreamer inside the well-casing, showing the cutters retracted. Fig. 2 is similar to Fig. 1 of the drawings, except that the reamer is projecting below the bottom of the well-casing, and the cutters are shown extended in operative position. Fig. 3 is a transverse section taken in the direction of the arrows on the line $w-w$ of Fig. 1 of the drawings. Fig. 4 is a transverse section 45 taken in the direction of the arrows on the line $x-x$ of Fig. 1 of the drawings. Fig. 5 is a transverse section taken in the direction

of the arrows on the line $y-y$ of Fig. 1 of the drawings. Fig. 6 is a transverse section taken in the direction of the arrows on the line $z-z$ of Fig. 1 of the drawings. Fig. 7 is a part-sectional elevation, showing the reamer partly withdrawn into the well-casing, the cutters being unlocked. Fig. 8 is an elevation, parts broken away, showing the 60 reamer almost entirely withdrawn into the well-casing, and the cutters partially retracted. Fig. 9 is an elevation of the reamer taken at right angles to Fig. 7 of the drawings, the well-casing being omitted. Fig. 10 is a part-sectional detail, enlarged, of the 65 key and a portion of the expanding rod. Fig. 11 is a side elevation, enlarged, of one of the cutters. Fig. 12 is a detailed face elevation, enlarged, of one of the cutters and a portion 70 of the body. Figs. 13 and 14 are side and face elevations respectively, enlarged, of one of the trip-blocks. Fig. 15 is a detailed side elevation, enlarged, of the expanding wedge and a portion of the expanding rod. 75

In the drawings, the numeral 1 represents the body of the underreamer, which is substantially cylindrical in form, as shown particularly in Fig. 9, and of a diameter to fit loosely within the well-casing 2, Figs. 1 to 8. 80 At its upper end, this body 1 is provided with any suitable means for attachment to a cable or rod, not shown in the drawings, as, for example, a tapered screw-thread 3. At the lower end of said body there is formed a 85 transverse slot 4, Fig. 9 of the drawings, having its central portion widened as at 5, Fig. 6 of the drawings, to form shoulders 6.

The reaming cutters 8, Figs. 1, 2, 7, 8, 9, 11 and 12 of the drawings, are formed with upwardly extending narrowed tongues 9, adapted to lie within the slot 4 in the body 1. Lateral shoulders 10 on said tongues 9 engage the shoulders 6 in the slot 4, to limit the outward movement of the cutters, as shown 95 in Fig. 6 of the drawings. Said cutters are provided with elongated pivot holes 11, through which pass transverse pivot pins 12 secured in the body 1. Cotter pins 13, Fig. 6 of the drawings, retain said pivot pins 12 in 100 position.

The lower ends of the cutters 8 are relatively wide, as shown in Figs. 9 and 12 of the drawings, to provide ample surface for

the cutting edges 14. The shoulders 15 formed by the tops of said wide portions are adapted to bear against the flat lower end 16 of the body 1 when the cutters are in the 5 expanded position, as in Figs. 2 and 7 of the drawings, to provide support for said cutters. In addition to the support thus provided, the upper ends of the tongues 9 have semi-circular bearings in the base of the slot 19 4, as shown at 17 in Figs. 9 and 12 of the drawings, the purpose of said semi-circular seats being to provide firm support for said cutters at these points in the event of lateral wear in the notch 4 and on the tongues 9, 15 which would cause said tongues to assume a position indicated by the dotted lines 18 in Fig. 12 of the drawings.

Each of the cutters 8 is provided with an inclined inner surface 19, Figs. 11 and 12 of the drawings, of which the upper end is raised, as at 20, and the lower end is depressed between the opposite flared raised guide lugs 19'. A central longitudinal groove 21 is cut in said surfaces 19 and 20, 25 as shown in the drawings. A centrally disposed expanding wedge 22, provided as shown in Figs. 1, 2, 7, 8, 9 and 15 of the drawings, with opposite inclined faces 23 having a raised central portion 24, adapted 30 to engage respectively the inclined surfaces 19 and the groove 21 therein, of the cutters 8, is fixed upon the end of a slidable expanding rod 25, which extends through an axially disposed bore 26 in the body 1. Said wedge 35 22 is also provided at its upper end with cam faces 27, and at its lower end with a flat point 28 to act as a drill-bit to loosen any material and chips from the sides of the well which would otherwise collect in the 40 center between the cutters and interfere with the proper action of the reamer.

The upper end of the axial bore 26 is enlarged to form a chamber 29, within which, and surrounding the rod 25, a spiral compression spring 30 is located. An adjustable collar, shown in Figs. 1, 7 and 8 of the drawings, as a nut 31 with a lock-nut 31', is provided on the upper end of the rod 25 to take the thrust of said spring 30. It will be seen from the drawings that the spring 30 acts to draw the rod 25 upward, thus forcing the wedge 22 between the cutters 8. The wedge faces 23 coat with the inclined inner faces 19 of said cutters to force the same 50 apart, and bring them into their expanded or operative position, as shown in Fig. 2 of the drawings, so that the cutting edges 14 bear against the sides of the well, and ream the same out from its original diameter indicated at 32, to a greater diameter 32', to permit the sinking of the casing 2.

The inclination of the interengaging expanding faces 23 and 19 is so slight that no ordinary amount of radial pressure exerted 60 on the exterior surfaces of the cutters 8 is

sufficient to move the wedge downward against the compression of the spring 30. Thus the cutters are securely locked in their expanded position, and cannot be retracted by the reaction of the pressure of their cutting edges against the sides of the well. 70

Means for automatically retracting the cutters is provided as follows:—The body 1 is formed with oppositely disposed upwardly inclined longitudinal grooves 33, 75 Figs. 1, 2, 4, 7 and 9 of the drawings, provided with lateral flanges 34 forming guide-ways 35. The lower ends of said grooves are further depressed, as at 36 in Figs. 1, 2 and 7 of the drawings. Within each of said 80 grooves 33 is loosely mounted, for free sliding movement, a trip-block 37, Figs. 1, 2, 7, 9, 13 and 14 of the drawings, provided with lateral flanges 38 adapted to engage the guide-ways 35, and further provided with a 85 transverse slot 39, an exterior raised surface 40, ending at its upper end in a shoulder 41, and interior raised surfaces 42 and 43.

The central expanding rod 25 has extending through it a fixed transverse key 44, 90 Figs. 1, 2 and 7 of the drawings, which also extends loosely through a central slot 45 in the body 1 and through the slots 39 in the trip-blocks 37. This key consists, as shown particularly in Fig. 10 of the drawings, of two interengaging wedge members 44' and 44'', the lower one of which 44', is provided with spaced lugs 46, adapted to hold said member when in locked position against lateral movement in the expanding rod 25. A 100 bolt 47 retains the two wedge members 44' and 44'' in vertically expanded position to prevent up and down movement with respect to the rod 25. Thus the key when assembled is securely locked in position in 105 said rod 25.

When the reamer is pulled up into the well-casing from the position shown in Fig. 2 of the drawings, the shoulders 41 on the trip-blocks 37 engage a collar 48 mounted 110 upon the lower end of the well-casing 2, said collar 48 being preferably formed with a counter-bored lower edge 49. This engagement causes the trip-blocks 37, the key 44, the rod 25, and the wedge 22 to remain 115 stationary, while the body 1 with the cutters 8 moves upward to the position of Fig. 7 of the drawings. Further movement then permits the lower ends 42 of the blocks 37 to drop into the depressed portions 36 of the 120 grooves 33, thereby freeing the shoulders 41 from engagement with the collar 48, so that the blocks are drawn up into the casing with the body, until the cutters 8 reach the collar 48. At this point the engagement of 125 the inclined outer surfaces 9' of said cutters 8 with the collar 48 forces said cutters inward, as shown in full lines in Fig. 8 of the drawings, and in so doing, the inner surfaces 19 of the cutters engage with the in- 130

clined faces 27 of the wedge 22, and force the same downward a slight distance to draw the blocks 37 farther down in their inclined grooves 33, thus freeing their outer surfaces 5 40 from contact with the interior of the casing 2, and to allow the cutters to assume their fully retracted or closed position, shown in broken lines in said Fig. 8 of the drawings, in which position the entire device 10 can be drawn through the well-casing 2, as shown in Fig. 1 of the drawings.

The reverse of the above described operation permits the spring 30 to actuate the wedge 22 for raising the same through the 15 medium of the rod 25 for opening or expanding the cutters to operative position.

I do not wish to limit myself to the particular construction herein described, but on the contrary, I wish to claim the essential 20 principles of the invention as broadly as the state of the art will permit.

Having thus described my invention what I claim as new and desire to protect by Letters Patent is:—

25 1. In an underreamer, in combination with a body portion adapted to be passed through the casing of a well and provided with a transverse slot, a pair of cutter members fulcrumed in said slot, and having substantially 30 semi-cylindrical seats in the base thereof, means for automatically expanding said cutters, and devices coacting with the well casing for retracting said cutters to enable the same to pass through said casing.

35 2. In an underreamer, in combination with a body portion adapted to be passed through the casing of a well and provided with a transverse slot in its lower end, a plurality of fulcrumed cutter members provided with 40 shoulders adapted to bear against the lower end of said body and upwardly extending tongues adapted to lie within said slot and having substantially semi-cylindrical seats in the base thereof, means for automatically 45 expanding said cutters, and devices coacting with the well casing for retracting said cutters to enable the same to pass through said casing.

50 3. In an underreamer, in combination with a body portion adapted to be passed through the casing of a well and provided with a transverse slot in its lower end, a plurality of cutter members having loose pivotal connection with said body and being provided 55 with upwardly extending tongues adapted to lie within said slot and having substantially semi-cylindrical seats in the base thereof, means for automatically expanding said cutters, and devices coacting with the well casing for retracting said cutters to enable the same to pass through said casing.

55 4. In an underreamer, in combination with a body portion adapted to be passed through the casing of a well and provided with a transverse slot and a plurality of pivot-pins

extending across said slot, a plurality of cutter members provided with shoulders adapted to bear against the lower end of said body and upwardly extending tongues adapted to lie within said slot and having substantially semi-cylindrical seats in the base thereof, said tongues having transverse slots therethrough adapted to provide loose pivotal connection with said pins, means for automatically expanding said cutters, and devices coacting with the well casing for retracting said cutters to enable the same to pass through said casing.

5. In an underreamer, in combination with a body portion adapted to be passed through the casing of a well and provided with a transverse slot and a plurality of pivot-pins extending across said slot, a plurality of cutter members provided with shoulders adapted to bear against the lower end of said body and upwardly extending tongues adapted to lie within said slot and having substantially semi-cylindrical seats in the base thereof, said tongues having transverse slots therethrough adapted to provide loose pivotal connection with said pins, a spring actuated wedge member having inclined faces adapted to be inserted between and to engage said cutter members for automatically expanding the same, and devices coacting with the well-casing for withdrawing said wedge to permit said cutters to be retracted to pass through said casing.

6. In an underreamer, in combination with a body portion adapted to be passed through the casing of a well, a plurality of cutter members fulcrumed in the lower end of said body, a spring actuated wedge member having inclined faces adapted to be inserted between and to engage said cutters for automatically expanding the same, said wedge being further provided with a lower cutting edge, and devices coacting with the well-casing for withdrawing said wedge to permit said cutters to be retracted to pass through said casing.

7. In an underreamer, in combination with a body adapted to be passed through the casing of a well, and provided with a pair of longitudinally disposed grooves in the surface thereof, the bottoms of said grooves being formed with abrupt shoulders separating relatively shallow portions from relatively deep portions, cutter members pivotally mounted in the lower end of said body; means for expanding said cutters; and means for retracting said expanding means comprising a pair of trip blocks slidably mounted in said grooves, each of said blocks being provided with an outwardly projecting shoulder adapted to engage the lower end of the well-casing when said block is wholly within the shallow portion of its groove, and to disengage the same when partly within the deep portion thereof; and

connecting devices between said blocks and said expanding means.

8. In an underreamer, in combination with a body adapted to be passed through the casing of a well, and provided with longitudinally disposed grooves in the surface thereof, each of said grooves being formed with a relatively shallow upper portion and a relative deep, lower portion separated therefrom by an abrupt shoulder, cutter members pivotally mounted in the lower end of said body; means for expanding said cutters; and means for retracting said expanding means comprising a trip block slidably mounted in each of said grooves, said blocks being provided with outwardly projecting shoulders adapted to engage the lower end of the well-casing when said blocks are wholly within the shallow portions of said grooves, and to disengage the same when partly within the deep portions thereof; and connecting devices between said blocks and said expanding means.

9. In an underreamer, in combination with a body adapted to be passed through the casing of a well, and provided with longitudinally disposed grooves in the surface thereof, each of said grooves being formed with a relatively shallow upper portion and a relative deep lower portion separated therefrom by an abrupt shoulder, cutter members pivotally mounted in the lower end of said body; means for expanding said cutters; and means for retracting said expanding means, comprising an elongated trip block slidably mounted in each of said grooves, each of said blocks being provided on its inner surface with bearing faces adapted to follow the bottom of its groove, and on its outer surface with an outwardly projecting shoulder adapted to engage the lower end of the well-casing when said inner bearing faces lie in the shallow portion of said groove, and to disengage the same when partly within the deep portion thereof; and connecting devices between said blocks and said expanding means.

10. In an underreamer, in combination with a body adapted to be passed through the casing of a well, and provided with longitudinally disposed grooves in the surface thereof, said grooves being formed with relatively shallow upper portions and relatively deep lower portions separated therefrom by abrupt shoulders, cutter members pivotally mounted in the lower end of said body; means for expanding said cutters; and means for retracting said expanding means, comprising elongated trip blocks slidably mounted in said grooves, said blocks being provided on their inner surfaces with spaced raised bearing faces adapted to follow the bottom of said grooves, and on their outer surfaces with outwardly projecting shoulders adapted to engage the lower end of the

well-casing when said inner bearing faces lie in the shallow portions of said grooves, and to disengage the same when the lower inner bearing faces lie in the deep lower portions of said grooves; and connecting devices between said blocks and said expanding means.

11. In an underreamer, in combination with a body portion adapted to be passed through the casing of a well and having a pair of oppositely disposed longitudinal slots in the surface thereof, a pair of cutter members fulcrumed in the lower end of said body, a wedge member adapted to be inserted between said cutters to expand the same, said wedge being carried by a longitudinal sliding rod having a transverse slot formed therein, and means for controlling the movement of said rod comprising a pair of trip-blocks slidably mounted within the grooves in said body, said blocks being provided with transverse slots therethrough and exterior shoulders adapted to engage the lower end of the well-casing, and a transverse key fixed in the slot in said sliding rod and engaging with the transverse slots in said blocks, said key comprising a pair of interengaging wedge members one of which is provided with spaced lugs adapted to lie on either side of said rod to prevent lateral movement of the key with respect thereto, and means for locking said wedge members in position.

12. In an underreamer, in combination with a body portion adapted to be passed through the casing of a well and having a pair of oppositely disposed longitudinal slots in the surface thereof, a pair of cutter members fulcrumed in the lower end of said body, a wedge member adapted to be inserted between said cutters to expand the same, said wedge being carried by a longitudinal sliding rod having a transverse slot formed therein, and means for controlling the movement of said rod comprising a pair of trip-blocks slidably mounted within the grooves in said body, said blocks being provided with transverse slots, therethrough and exterior shoulders adapted to engage the lower end of the well-casing, and a transverse key fixed in the slot in said sliding rod and engaging with the transverse slots in said blocks, said key comprising a pair of interengaging wedge members one of which is provided with spaced lugs adapted to lie on either side of said rod to prevent lateral movement of the key with respect thereto, and a bolt lying in the plane of contact of the interengaging faces of said wedge members for retaining the same in their respective positions.

13. In an underreamer, in combination with a body portion adapted to be passed through the casing of a well and provided with a transverse slot in its lower end, a plu-

- rality of cutter members having loose pivotal connection within said transverse slot, and being provided with upwardly extending tongues adapted to lie within said slot and having substantially semi-cylindrical seats in the base thereof, a spring actuated wedge member having inclined faces adapted to be inserted between and to engage said cutters for automatically expanding the same, said wedge being further provided with a lower cutting edge, and devices coacting with the well-casing for withdrawing said wedge to permit said cutters to be retracted to pass through said casing.
- 15 14. In an underreamer, in combination with a body portion adapted to be passed through the casing of a well and provided with a transverse slot in its lower end and a plurality of inclined longitudinal grooves 20 in the surface thereof, a plurality of cutter members having loose pivotal connection within said transverse slot, and being provided with upwardly extending tongues adapted to lie within said slot and having substantially semi-cylindrical seats in the base thereof, a spring actuated wedge member having inclined faces adapted to be inserted between and to engage said cutters for automatically expanding the same, said wedge being further provided with a lower cutting edge, and devices for retracting said cutters comprising a plurality of trip-blocks slidably mounted in said longitudinal grooves and adapted to engage the bottom of 30 the well casing, and connecting devices between said blocks and said wedge member.
15. In an underreamer, in combination with a body portion adapted to be passed through the casing of a well and having inclined longitudinally disposed grooves in the surface thereof, cutter members pivotally mounted in the lower end of said body portion, means for expanding said cutters, and means for retracting said expanding 40 means comprising trip blocks slidably mounted in said grooves, said blocks being provided with outwardly projecting shoulders adapted to engage the lower end of the well-casing, and with elongated longitudinal exterior surfaces below said shoulders adapted to bear against the interior of said well-casing when the reamer is passed therethrough, and connecting devices between said blocks and said expanding means.
- 55 16. In an underreamer, in combination with a body portion adapted to be passed through the casing of a well and having inclined longitudinally disposed grooves in the surface thereof, cutter members pivotally mounted in the lower end of said body portion, means for expanding said cutters, and means for retracting said expanding 60 means comprising trip blocks slidably mounted in said grooves, said blocks being provided with relatively thin upper portions
- adapted to enter the well-casing and bear against the sides thereof, with outwardly projecting shoulders adapted to engage the lower end of said well-casing, and with elongated longitudinal exterior surfaces below said shoulders adapted to bear against the interior of said well casing when the reamer is passed therethrough, and connecting devices between said blocks and said expanding means.
- 75 17. In an underreamer, the combination with a bored body adapted to be passed through the casing of a well, of cutter members pivotally mounted within the lower end of said body and provided with inner bearing surfaces, a spring held expanding member movable between said cutter members and provided with outer bearing surfaces adapted to coact with the bearing surfaces of said members for the expansion thereof on the inward movement of the expanding member and further provided at its upper end portion with inwardly inclined cam surfaces for engagement with the cutter members on the final closing movement thereof, a trip member slidably on the body of the underreamer for engagement with the bottom of the well casing to force outwardly the expanding member on the inward movement of the underreamer within the well casing, and connection between the trip member and the expanding member for actuating the wedge member and moving the trip member free of contact with the inner wall surface of the well casing through the action of the cutter members on the cam surfaces of the wedge member during the final closing movement of said cutting members.
- 80 18. In an underreamer, the combination with a bored body adapted to be passed through a well casing, of cutter members pivoted within the lower end portion of said body for swinging movement and provided on their inner faces with inwardly inclined bearing surfaces and further provided at their upper end portions with inwardly inclined cam surfaces, a spring held wedge member movable between the cutter members and provided with inclined bearing surfaces and further provided at its inner end with cam surfaces for co-action with the bearing surfaces and the cam surfaces of the cutter members, a trip member slidably mounted on the body of the underreamer, and connection between the trip member and the wedge member.
- 85 19. In an underreamer, the combination with the body thereof, of cutter members pivotally mounted in the lower end thereof for swinging movement and provided with inner bearing surfaces and further provided with inwardly inclined cam surfaces, an expanding member movable between the cutter members and provided with bearing surfaces
- 90 95 100 105 110 115 120 125 130

which co-act with the bearing surfaces of the cutter members and further provided with cam surfaces for coaction with the cam surfaces of said cutter members, and means carried by the body of the underreamer for actuating said expanding member.

In testimony whereof I have signed my

name to this specification in the presence of two subscribing witnesses.

WILLIAM M. KECK.
